DESIGN FOR A DISPLAY STAND

Frank L. Dale and Edward P. Lea, New York, N. Y., assignors to Riegel Textile Corporation, New York, N. Y., a corporation of New York

Application August 24, 1940, Serial No. 94,599

Term of patent 7 years

To all whom it may concern:

Be it known that we, Frank L. Dale and Edward P. Lea, citizens of the United States, residing, respectively, at 50 Riverside Drive, New York city, New York, and Park Avenue and 37th Street, New York city, New York, have invented a new, original, and ornamental Design for a Display Stand, of which the following is a specification, reference being had to the accompanying drawing, forming part thereof.

We claim.

The ornamental design for a display stand, substantially as shown.

FRANK L. DALE.
EDWARD P. LEA.
